(57) **CLAIM**

The ornamental design for a head portion of a ratchet wrench, as shown and described.

DESCRIPTION

FIG. 1 is a perspective view of a head portion of a ratchet wrench showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view showing the utilization of head portion of a ratchet wrench.

The dash-dash broken lines on the head portion of the ratchet wrench illustrate features that form no part of the claimed design. The long-dash-short-dash line represents the boundary of the claim and forms no part of the claim. The broken line showing of a ratchet wrench handle in FIG. 8 is included for the purpose of illustrating environment of use of the article in which the design is embodied and forms no part of the claimed design.

The shaded surfaces and the solid lines represent the claimed portions of the design.
